TORCH

Almanzo Schaff, Waterbury, Conn., assignor to
Seovill Manufacturing Company, Waterbury,
Conn., a corporation of Connecticut

Application November 5, 1931. Serial No. 573,054

3 Claims. (Cl. 158—35)

The present invention relates to hydrocarbon torches.

It is an object of the invention to provide certain improvements over the U. S. patent to Carlton, No. 901,307, dated October 13, 1908.

It is a particular object of the invention to provide an improved form of such a torch in order to permit its use with so-called ordinary or straight gasoline, the improved form of torch being useable as well with so-called high test gasoline, but its use being not necessarily restricted thereto.

The invention comprises a member cooperating with the torch spout and providing therefor a preheating chamber because of which the torch is enabled to operate satisfactorily and effectively with fuel other than high test gasoline.

Other features and advantages of the invention are hereinafter more fully described in connection with the accompanying drawing, which illustrates a preferred embodiment of the invention and in which the Figure 1 is a side elevation of a torch provided with a preheating chamber constructed in accordance with the invention and constituting a preferred embodiment thereof; and Figure 2 is a vertical sectional view through the upper portion of the torch of Figure 1.

Referring in detail to the accompanying drawing the torch embodying the present invention includes a fuel reservoir 13 provided at its top with a threaded filling opening into which, and containing the wick 12, is screwed the spout member 15 of the torch. The spout member 15 is provided at its lower end with manually operable turning wings 16 by means of which the spout may be readily screwed into position, the flexible washer 17 being provided between the spout member and the reservoir.

The spout 15 is preferably bent as shown in the drawing and is provided on its under side, including the under side of the bent portion, with a series of indentations forming ridges, and at its upper end is provided with screw threads 19 for attachment thereto of a burner sleeve 21. The burner sleeve 21 is provided intermediate its ends with cooperating screw threads 22 and is also provided, between said screw threads and its upper open end, with a plurality of air admitting openings 24. In accordance with the present invention the burner sleeve 21 extends downwardly or rearwardly beyond its screw threads 22 around the upper end of the spout 15, being spaced from said spout and thereby providing around the upper end of the spout a preheating chamber 25. It will be understood that the upper end of the

spout is closed except for the usual small blow hole. The provision of the preheating chamber 25 makes it possible to use other fuels than high test gasoline with the result that the torch is not limited to use with such fuel.

In using the torch, a lighted match, or candle, or suitable flame from any source is held close to the indented ridges of the spout, the heat from the flame being trapped and retained close to the spout by the preheating chamber, vaporizing the fuel with such efficiency that fuels other than high test gasoline may be used. As soon as sufficient pressure is generated, the vapor is forced out of the spout opening, and, mixed with air in the upper part of the burner sleeve, may be ignited at the upper opening of said sleeve. The preliminary heating of the spout may now be dispensed with, the torch flame continuing until blown out or exhaustion of fuel.

By reason of the preheating chamber, after the burner is ignited, the preheating of the fuel continues, being caused by the burning flame and the preheating chamber. This preheating of the fuel prior to its combustion continues while the torch is ignited. It will be noted that the preheating chamber surrounds that part of the feeding tube which contains the fuel before it passes out through the ignition opening. Whether or not it is the case that by reason of the preheating, fuel, such as gasoline, is vaporized before it passes through the ignition opening, it is a fact that with the present invention a low test gasoline is responsive and operable, whereas, without the present invention, high test gasoline would be required.

What is claimed is:

1. A torch including a reservoir provided with a supporting base, a spout in communication with said reservoir and extending upwardly therefrom, a wick in said spout reaching into said reservoir, said spout having a blow hole, means on said spout for attaching a burner sleeve thereto, and a burner sleeve attached to said spout extending forwardly therefrom and forming a preheating chamber around said spout between the blow hole and said reservoir.

2. A torch including a reservoir, a spout in communication therewith, a wick in said spout reaching into said reservoir, said spout having a blow hole, means on said spout for attaching a burner sleeve thereto, and a burner sleeve attached to said spout extending forwardly therefrom and having its rearward portion surrounding said spout and spaced therefrom, providing a preheating chamber for said spout between said

reservoir and the burner sleeve attaching means on said spout.

3. A torch including a reservoir, a bent spout in communication therewith, a wick in said spout reaching into said reservoir, said spout having a series of indentations on its under side, said spout having a blow hole and having threads for

attachment of a burner sleeve, and a burner sleeve attached to said spout extending forwardly thereof beyond said blow hole and extending rearwardly around and spaced from said spout between said threads and said reservoir thus forming a preheating chamber around said spout.
